UNITED STATES PATENT OFFICE

CISRO FURLEW, OF DYERSBURG, TENNESSEE

COLLAPSIBLE PARACHUTE ATTACHMENT FOR AEROPLANES

Application filed March 6, 1929. Serial No. 344,813.

The invention appertains to heavier than air machines, chiefly of the type equipped with planes, and provides for a safe descent in an emergency or when desired.

5 The invention contemplates a parachute mounted upon the machine, as a part thereof, and normally collapsed, but automatically expansible independently of air pressure, whereby its opening is positively assured.

10 The invention provides a parachute which while normally folded, is in position for instant use, being urged into action by spring means, and held inactive by latch means which when released admits of the parachute

15 instantly expanding under the action of the spring means to assure a safe landing of the machine.

While the drawing illustrates a preferred embodiment of the invention, it is to be understood that in adapting the means to meet specific needs and requirements, the design may be varied and such other changes in the minor details of construction may be resorted to within the scope of the invention as 25 claimed, without departing from the spirit thereof.

For a full understanding of the invention and the merits thereof, reference is to be had to the following description and the drawing 30 hereto attached, in which:—

Figure 1 is a top plan view of an aeroplane equipped with a self expanding parachute embodying the invention.

Figure 2 is a side view of the machine showing the parachute expanded.

Figure 3 is an enlarged vertical, transverse sectional view on the line 3—3 of Figure 2, the parachute being collapsed or folded and the outer ends of the wings being broken away.

Figure 4 is a fragmentary sectional view showing the joint formed between the sections of the parachute.

Corresponding and like parts are referred 45 to in the following description and designated in the several views of the drawings by like reference characters.

The numeral 1 designates the body of the flying machine and 2 the wings. These parts 50 may be of any well known construction and

arrangement and are illustrated to demonstrate the application of the invention.

A ring 3 is supported above the machine in any determinate way as by means of straps 4. The parachute when collapsed lies within the plane of the ring 3 and is connected thereto in any preferred manner. The parachute is of sectional formation and in the preferable construction embodies two similar or like parts. Each of the sections presents the outline of a quarter sphere. The bottom edge of the sections is attached to the fixed ring 3, whereas the moving edge of each of the sections is attached to a semi-circular bar 5. The semi-circular bars 5 are pivotally connected at their ends, as indicated at 6, and form a ring of less diameter than the ring 3. The fabric portion 7 of the parachute is adapted to fold within the space formed between the outer fixed ring 3 and the inner sectional ring, as indicated most clearly in Figure 3 of the drawings, so as to be out of the way and protected. When the parachute is expanded it presents the appearance of a semi-sphere so as to function in a manner well understood.

Contractile helical springs 8 normally tend to hold the parachute expanded and these springs are under tension when the parachute is collapsed or folded, as indicated in Figure 3 of the drawings, whereby to instantly expand the parachute when released from the restraining means. Arms 9 project upwardly from the ring 3 at diametrically opposite points and a pair of springs 8 are connected at one end to each of the arms 9 and at the opposite end to the section 5. A latch 10 is provided for each of the sections 5 and is pivoted to the fixed ring 3. The latches 10 engage each of the parts 5 of the inner sectional ring and hold them in the plane of the outer fixed ring 3 against the tension of the springs 8. The latches 10 are spring actuated and are operable from a convenient point by means of cords 11 which pass over suitably disposed guide pulleys and are attached to a drum 12 which when rotated to exert a pull upon the cord 11 operates the latches 10 to release the parts 5 which are instantly thrown upwardly and expand the parachute 100

independently of any air pressure. The sections 5 overlap when thrown upwardly, as indicated most clearly in Figure 4 of the drawings. A stop 13 on one of the sections 5 engages the companion part and limits the movement of the sections when thrown into operative position by means of the springs 8.

By locating the parachute above the machine it is out of the way and the load is suspended therebelow when the parachute is expanded. The spring means for expanding the parachute may be of any determinate construction and arrangement found most advantageous in the adaptation of the invention to a particular make or type of machine. The latch means for holding the parachute collapsed, and the control for the latch means may be of any arrangement best adapted to meet existing conditions. In an emergency the latch means are operated to release the sections of the parachute, and the spring means instantly operate to expand the parachute whereby making it unnecessary for the machine to drop to cause the parachute to expand. Moreover the arrangement precludes any possibility of the parts becoming entangled as frequently happens and is the cause of the parachute to properly function.

Having thus described the invention, I claim:

1. A parachute attachment for a flying machine, the same comprising a ring, a sectional ring pivoted to the first mentioned ring, a sectional parachute having the bottom edge of the sections connected to the first mentioned ring, and having the opposite edge portions connected to the respective sections of the ring including the pivoted parts, spring means normally tending to expand the parachute, and latch means for holding the sections folded against the action of the expanding spring means.

2. A parachute attachment for a flying machine, the same comprising a fixed ring, a sectional ring in the plane of the fixed ring and spaced therefrom, and having the sections pivoted thereto, a sectional parachute having the bottom edge of the sections connected to the fixed ring, and the opposite edge connected to the respective pivoted sections, the parachute when collapsed occupying the space formed between the two rings, spring means between the two rings normally urging the pivoted sections into position for expanding the parachute, and latch means mounted upon the fixed ring and engageable with the pivoted sections to hold the parachute collapsed.

3. The combination with an aeroplane, of a fixed ring mounted thereon, a sectional ring pivoted to the fixed ring and spaced therefrom, a sectional parachute having the bottom edge connected to the fixed ring and the opposite edge connected to the respective pivoted sections, the parachute when collapsed

70 folding into the space formed between the two rings, spring means normally tending to expand the parachute, latch means for holding the parachute collapsed against the tension of the expanding spring means, and means under control of the operator for actuating the latch means to effect release of the parachute to admit of its instant expansion by the said spring means.

4. A parachute attachment for a flying machine including spaced concentric members, one of the members being fixed and the other member comprising opposed pivoted sections, a self-expansible parachute normally housed in the space formed between the aforesaid members and comprising complementary parts, both parts of the parachute being connected to the fixed member and each of the said parts being connected to a pivoted section of the beforementioned sectional member, and means normally holding the parachute housed between the said concentric members and releasable at will of the operator.

5. A parachute attachment for a flying machine including spaced concentric rings, the outer ring being fixed and the inner ring comprising semi-circular bars pivotally connected at their inner ends, an expandible parachute normally housed between the rings and comprising parts, each of said parts when expanded approximating the outline of a quarter sphere and attached at one edge to a pivoted ring section, and both parts being attached to the outer fixed ring, spring means normally urging the pivoted ring sections into operative position to expand the parachute, and means for holding the parachute collapsed and releasable by the operator to permit automatic expansion of the parachute.

In testimony whereof I affix my signature.
